UNITED STATES PATENT OFFICE

2,226,207

MAGAZINE RIFLE

Louis Nolan Nomar, Charleston, W. Va.

Application July 22, 1938, Serial No. 220,800

10 Claims.

(Cl. 42—19)

This invention relates to a magazine rifle.

The invention aims to provide, in a manner as hereinafter set forth, a rifle of the class referred to including means whereby rapid automatic firing of the cartridges is obtained.

The invention further aims to provide, in a manner as hereinafter set forth, a rifle of the class referred to including means whereby rapid automatic disposing of the cartridges successively 10 in position to be fired is had.

The invention further aims to provide, in a manner as hereinafter set forth, a rifle of the class referred to including new and novel means for locking the breech block in position for subsequent firing.

The invention further aims to provide, in a manner as hereinafter set forth, a rifle of the class referred to including new and novel means for projecting the shells of the fired cartridges 20 therefrom.

The invention further aims to provide, in a manner as hereinafter set forth, a rifle of the class referred to, including new and novel means for successively positioning the cartridges in the 25 path of and acted upon by the breech block on its successive return movements to force the cartridges into the rifle barrel.

The invention further aims to provide, in a manner as hereinafter set forth, a rifle of the 30 class referred to, including means for obtaining a positive locking of the breech block, when a cartridge is in firing position thereby preventing the impairing of the rifle when the cartridge is fired.

The invention further aims to provide, in a manner as hereinafter set forth, a rifle of the 35 class referred to including a sear means for normally latching the hammer of the rifle from action, and a safety device for latching said sear 40 means in latching relation with respect to the hammer.

The invention further aims to provide, in a manner as hereinafter set forth, a rifle of the 45 class referred to including a sear means for normally latching the hammer of the rifle from action, a trigger element operated means for shifting the sear means to released position relative to the hammer, and means for controlling 50 the operation of the said trigger element operated means.

The invention further aims to provide, in a manner as hereinafter set forth, a trigger element operated means for shifting a sear means 55 to inactive position and means for releasably re-

taining said trigger element operated means in neutral position relative to the sear means.

The invention further aims to provide, in a manner as hereinafter set forth, a rifle of the class referred to including a shiftable slidably 5 mounted trigger element for actuating the operating means for a sear means, a handle in which said trigger element is slidably mounted, and a releasable safety lock arranged within the handle for normally maintaining said trigger element from actuating said operating means.

The invention further aims to provide, in a manner as hereinafter set forth, a rifle of the class referred to so constructed and arranged as to provide a steady continuous fire or a controlled fire.

The invention further aims to provide, in a manner as hereinafter set forth, a rifle of the class referred to having its parts so constructed and arranged to reduce frictional heat to a minimum.

The invention further aims to provide, in a manner as hereinafter set forth, a rifle of the class referred to including a new and novel cartridge feeding means for successively delivering 25 cartridges from a magazine arranged within the stock of the rifle.

The invention further aims to provide, in a manner as hereinafter set forth, a rifle of the class referred to having its parts so constructed 30 and arranged to prevent the jamming of the rifle when the latter is fired.

The invention further aims to provide, in a manner as hereinafter set forth, a rifle of the class referred to which is comparatively simple 35 in its construction and arrangement, strong, durable, automatic in its action, thoroughly efficient in its use, readily assembled, expeditiously repaired when occasion requires, and comparatively inexpensive to manufacture.

To the above ends essentially and to others which may hereinafter appear, the invention consists of the novel construction, combination and arrangement of parts as will be more specifically referred to and illustrated in the accompanying drawings wherein is shown an embodiment of the invention, but it is to be understood that changes, variations and modifications may be resorted to which fall within the scope of the invention as claimed.

In the drawings:

Figures 1^a and 1^b are vertical sections on the longitudinal axis of the rifle and showing the operating mechanisms, the section 1^b being a continuation of the section 1^a,

- Figure 2 is an enlarged section on the line 2—2 of Figure 1^a.
- Figure 3 is an enlarged section on the line 3—3 of Figure 1^a.
- 5 Figure 4 is an enlarged section on the line 4—4 of Figure 1^b.
- Figure 5 is a plan view of the pusher device removed from the gun.
- Figure 6 is a fragmentary section on the line 10 6—6 of Figure 1^b.
- Figure 7 is a section through the pusher on the line 7—7 of Figure 1^b.
- Figure 8 is a greatly enlarged section on the line 8—8 of Figure 1^b.
- 15 Figure 9 is a section similar to the upper central portion of Figure 1^a, but to an enlarged scale to better show the details.
- Figure 10 is a section on the line 10—10 of Figure 9.
- 20 Figure 11 is a section on the line 11—11 of Figure 9.
- Figure 12 is a section on the line 12—12 of Figure 9.
- Figure 13 is a section on the line 13—13 of Figure 9.
- 25 Figure 14 is an enlarged section on the line 14—14 of Figure 1^a.
- Figure 15 is an enlarged section on the line 15—15 of Figure 1^a.
- 30 Figure 16 is a section on the line 16—16 of Figure 9.
- Figure 17 is a section on the line 17—17 of Figure 9.
- Figure 18 is a section on the line 18—18 of Figure 9.
- 35 Figure 19 is a section on the line 19—19 of Figure 9.
- Figure 20 is a fragmentary section on the line 20—20 of Figure 18.
- 40 Figure 21 is a plan view showing the breech block and adjacent parts.
- Figure 22 is a fragmentary section taken horizontally through the axis of the gun barrel.
- Figure 23 is a vertical section through the loading chamber and showing the breech block retracted.
- 45 Figure 24 is an isometric view of the breech block lock member and its arms.
- Figure 25 is an isometric view of the keeper for the breech block lock member.
- 50 Figure 26 is an isometric view of the hammer.
- Figure 27 is an elevation looking towards the outer face of a side cheek.
- Figure 28 is a view looking towards the front of the side cheeks when assembled showing the cartridge guide, and
- 55 Figure 29 is a section on line 29—29, Figure 1^a.
- The rifle includes a stock 1 (Figures 1^a, 1^b and 4) formed of a hollow member 2 of the desired width, thickness and length, disposed on its lower lengthwise edge, closed at its top, open at each end and open at its bottom. The member 2 provides a channel 3 having its side walls 4, 5 in proximity to their lower ends formed lengthwise thereof with the grooves 6, 7 respectively. The channel 3 opens at each end of member 2. The latter may be of any suitable contour in vertical section, preferably oval and is so shown. The member 2 is constructed from any suitable material preferably a species of hard wood. The rear end of member 2 is incurved. The forward end of member 2 inclines rearwardly from its bottom to its top. The grooves 6, 7 correspond in length to the length of the side walls 4, 5. The rear end 75 of member 2 has secured thereto a curved shoul-
- der plate 8 preferably constructed of metal and which provides for permanently closing the rear end of channel 3. The upper face of the forward end terminal portion 9 of member 2 inclines downwardly from rear to front as at 10. The rear end of the said inclined part terminates in a shoulder 11. The top of member 2 is formed with a cutout 12 which at its forward end opens through shoulder 11, Figure 21. The cutout 12 is disposed on the lengthwise center of member 2. The portion 9 directly below the bottom of cutout 12 has its inner face formed with an inwardly opening socket 13. The portion 9 is provided with an opening 14 which extends from bottom part 11 to socket 13. The member 2 in proximity to its forward end has one of its sides provided with a vertical opening 15 extending from the top to the bottom thereof.
- The stock 1 includes a metallic lining 16 throughout which snugly bears against the walls of channel 3. The sides of the lining conform in contour to the contour of the side walls of the channel. The latter opens at the bottom of member 2. The parts of the lining 16 which snugly engages the walls of the grooves 6, 7 provide oppositely disposed tracks 17, 18 of semi-cylindrical contour in vertical section opening into the channel and each of a length corresponding to the length of member 2. The channel 3 provides a magazine for a series of upstanding parallel closely related cartridges 19 slidably mounted in a clip 20 which is to be releasably held in the open bottom of member 2.
- The rifle includes a combined trigger, handle, cartridge abutment and cartridge guiding structure 21 (Figure 1^a) comprising a hand grip 22 which merges into a head 23 having a part 24 extended forwardly from the upper or inner end of the grip 22. The head 23 is formed with a groove 25 to provide it with a pair of arms 26 which abut the forward terminal portion of the bottom of member 2 adjacent the sides of the open bottom of channel 3. The lower portion of the forward end of groove 25 is closed by a bridge piece 27 provided at its top with a shoulder 28 and a seat 29 extending rearwardly from the lower end of shoulder 28. Positioned between the arms 26, bearing against shoulder 28 and mounted on seat 29 is the rigid horizontally disposed base 30 of a combined cartridge abutment and guiding element 31. The latter also includes an arm 32 having an upstanding forwardly inclined rigid lower portion 33, a curved upwardly extending forwardly directed rigid intermediate portion 34 and a curved forwardly directed resilient upper portion 35 of materially less thickness than the portion 34. The portion 33 is integral at its lower end with the forward end of the upper face of base 30. The latter has its front extended forwardly from the arms 26. The rear end of base 30 is positioned forwardly of the rear sides of the arms 26. The upper face of base 31 from a point removed from its forward to its rear end is inclined downwardly from front to rear to form an inclined seat 34 arranged below the top edges of arms 26 for supporting the forward end terminal portion of the cartridge clip 20 when loading the rifle. The bottom of base 30, in connection with the bridge piece 27 and bottom wall 35 of groove 25 provides a channel 36, in which is slidably mounted a trigger element 37, formed with a curved forward end edge 38 and provided in the upper part of its rear portion with a slot 39 inclining downwardly throughout from its for-

ward end. The element 31 is of less length than channel 36. The latter is closed at its forward end and open at its rear end. Access is had by the finger of a person to the channel 36, for the purpose of shifting element 31 rearwardly through the medium of a pair of aligning openings 40 formed in the head 23 in proximity to the forward end of the channel. The lower end of the rear side of the lower portion 33 of arm 32 is notched to form a groove 41 for a purpose to be referred to. The purpose of the slot 39 is for coupling with element 31 a releasable latching means for a sear structure. The manner in which the head 23, base 31 are connected together and with other portions of the rifle will be hereinafter referred to. The non-inclined portion of the base 31 is indicated at 42 and provides a seat for the butt end of the cartridge when the latter is forced off of the forward end of the clip 20, and when the cartridge is in such position, its flange extends into the groove 41 and permits of the shell of the cartridge bearing against the portion 33 of the arm 32. The said portion 33 of arm 32 constitutes an abutment, as well as a stop when the cartridge is forced in a forward direction from off of the clip 20. The cartridge is picked off of seat 42 and delivered for filing by a means to be referred to. The resilient upper portion 35 of the arm 32 forms a guide for the cartridge as the latter moves to loading position.

The rifle includes a pair of oppositely disposed side plates 43, 44 which not only coat to form a housing for a cartridge pick-up and delivery mechanism 45, but also for an operation means 46 common to said mechanism and to a cartridge feeding mechanism 47 for positioning the cartridges successively in the path of the pick-up and delivery mechanism 45. The plates 43, 44 in connection with holdfast devices, to be referred to also act to couple the stock 1, the structure 21, a combined deflecting and supporting element 48 and a supporting structure 49 common to a receiver or breech structure. The mechanisms 46, 47, the element 48 and the structure 49 will be more fully referred to.

Each of the side plates (Figure 27) is formed from a web of sheet metal 50 of the desired length, width and gauge having a horizontally disposed top edge 51 formed intermediate its ends with a notch 52, a vertical rear edge 53, an incurved lower corner edge 54, a bottom edge having a horizontal rear portion 55 and a depending outcurved forward portion 56 and a forward edge having an upper vertical portion 57, an incurved intermediate portion 58 and an outcurved lower portion 59 which merges into and is upon the same arc as the portion 56. The web 50 includes an inwardly disposed flange 60 which extends from the lower end of the front edge portion 57 to the forward end of the bottom edge portion 55. The flange 60 merges in and conforms in contour with the edge portions 56, 59. The web 50 is formed with an opening 61 and the material bordering the latter is outset as at 62. The web 50 in proximity to the edge portion 58 is provided with an opening 63, in proximity to edge 51 rearwardly of the notch 52 with a pair of spaced horizontally aligned openings 64, 65, in proximity to the edge portion 55 with a set of spaced horizontally aligned openings 66 as shown three in number, and above and in proximity to the forward opening 66 with an opening 67. When the side cheeks 43, 44 are anchored in position, they form an open top, open rear and closed bottom chamber 68 in which mechanism 45 operates and

through which passes the arm 32 of the mechanism 31. The arm 32 also passes through and extends upwardly from the mechanism 45.

The operating means 46 which is common to mechanisms 45, 47 consists of a rotatable hub or spool 69 (Figure 2) provided at its transverse center with an annular flange 70 and at its ends with annular flanges 71, 72 of materially less outer diameter than and spaced from the sides of the flange 70. The latter has its sides mortised to form a reduced portion 73 and a pair of annular shoulders 74, 75 (Figure 2). The outset portions 62 of the webs 50 form oppositely disposed recesses 76 which open into chamber 68. The hub 69 has its ends positioned in the recesses 74. Journaled in the openings 61 of the webs 50, extending through and fixed to the hub 69 at its lengthwise median, projecting from the plate 45 and through a motor chamber 76a, as well as journaled in the outer wall 77 of the latter is a power transmitting shaft 78. The motor chamber 76a is provided by an annular cup-shaped member 79 having its open end secured to the outset portion 62 of the plate 45. The motor employed is in the form of a windable power transmitting spring 80 having one end fixed to the shaft 78 and its other end to the member 79. The spring 80 is automatically wound in a manner as to be referred to, when the mechanism 47 is moved rearwardly in the stock 1 to an extent to permit of the loading of the rifle with a clip of cartridges.

The mechanism 45 includes a pair of spaced parallel combined pick-up and carrier elements 81 for the cartridges. The elements 81 are of like form and each consists of a plate 82 formed with an axial opening 83 for seating on a shoulder 74 or 75. The plate 82 when seated upon the shoulders 74, 75 have the reduced part 73 of flange 70 arranged between them. The plates 82 are fixedly secured to the said reduced part 73 by the holdfast means 84 whereby mechanism 45 will be carried with the hub 69. Each plate 82 is formed on its outer edge with a set of spaced combined cartridge pick-up and carrier lugs 84a of like form disposed substantially tangentially to the axis of the plate. Each lug 84a when in active position includes a leading edge 85, a follower edge 86 and an outer end edge 87. The leading edge of each lug extends from its inner to its outer end at an inward inclination towards its follower edge. The leading edges of the lugs provide seats for the butt ends of the cartridges. Each plate 82 is formed with a set of outer edge portions 88 and each extends at an outward inclination from the inner end of the leading edge of a follower lug to the inner end of the follower edge of a leading lug. The lugs are of a length, on the anti-clockwise movement of mechanism 45 to successively pick up and carry the cartridges which have been fed upon the seat 42. The plates 82 are so related whereby the lugs of one plate align with the lugs of the other, and the lugs of each pair of aligned lugs function in unison to pick up and carry a cartridge. When a cartridge is picked up and carried by mechanism 45, it seats lengthwise thereof against an edge portion 88 (see dotted line position Figure 1a). The mechanism 45 carries the cartridge from the dotted line showing aforesaid to the full line showing, Figure 10, which is above and on the resilient upper portion 35 of arm 32. The mechanism 45 forces the cartridge against the deflecting portion 89 of the element 48. The said portion 35 guides the cartridge to element 48 and in connection with the latter provides for the delivery of the

cartridge in the path of the breech block on its forward movement whereby the block will force the cartridge into the barrel.

The side plates 43, 44 are positioned against opposite sides of the element 48. The latter is apertured as at 90. The openings 63 in the webs 50 align with the aperture 90. Extending through the latter and the aligned openings 63 is a holdfast means 81 for coupling element 48 to the plates 43, 44. The head 22 and base 30 are formed with aligned openings 92, 93 which align with the openings 66 and 67 respectively and extended through the aligned openings 92, 66 and the aligned openings 93, 67 are holdfast means 94 for coupling structure 21 to the plates 43, 44. The structure 49 is formed with a pair of horizontally aligned openings 95, 96 which align with the openings 64, 65 respectively. Extending through the aligned openings 95, 64 and 96, 65 are holdfast means 97 for coupling structure 49 to the plates 43, 44. The plates 43, 44 coact to form a forward continuation of the channel 3, as at 98. The lining 16 is extended into the continuation 98. The structure 49 has its rear end abut shoulder 11 and is provided with a rearwardly extended apertured lug 99 arranged within the cutout 12. The lug 99 is anchored to member 2 by the holdfast means 100. The structure 49 has an inclined inner surface 101 which seats on the surface 10 of member 2. The means 100 is countersunk in lug 99, extends through opening 14 and arranged in socket 13.

The cartridge feeding mechanism 47 includes a pair of spaced pull members 102, 103 in the form of steel tapes which wind on hub 69 on the anti-clockwise movement of the latter and wind off hub 69 on the clockwise movement of the latter. The forward ends of the members 102, 103 are anchored on the outer periphery of hub 69 between the flange 70 and the flanges 71, 72 by the holdfast means 104. The member 102 when winding off or on, relative to hub 69 is arranged between flanges 70, 71 and member 103 between the flanges 70, 72. The rear ends of the tapes 102, 103 are connected to the forward terminal portions of a pair of spring controlled cylindrical coupling bars 104, 105 respectively slidably suspended in a slidably suspended pusher element 106. The forward end terminal portions 45 of the coupling bars are bifurcated, as at 107. The rear end terminal portions of members 102, 103 extend into the furcations and are anchored to the bars by the holdfast means, as at 108.

The element 106 includes a horizontally disposed oval-shaped hollow head part 109 open at its front, rear and centrally of its bottom. The part 109 has arranged therein a pair of spaced parallel transverse partitions 110, 111, each formed with a pair of spaced openings 112, 113. The openings 112 of the partitions align with each other. The openings 113 of the partitions align with each other. The bar 104 is slidably mounted in the aligned openings 112 and the bar 105 in the aligned openings 113. The manner 65 of mounting the bars 104, 105 slidably suspends them in head part 109. Each coupling bar has adjustably connected thereto a collar 114 arranged between the partitions. Carried by each coupling bar is a coiled cushioning spring 115 therefor which is interposed between the partition 110 and a collar 114.

The element 106 includes a depending yoke 116 having its sides 117, at the lower portions thereof formed with oppositely extending semi-circular outset portions 118. The base 119 of yoke 117 is

formed integral, at its rear portion with a depending finger grip 120 of ring-like form. The grip 120 is disposed at right angles to the partitions 110, 111. The yoke 116 corresponds in length to that of head part 109. The yoke sides 117 at the front thereof and above the outset portions 118 are connected together by a bridge piece 121 positioned below the head part 109. The yoke base 119 is cutout, as at 122 at its forward end to provide a clearance. The rear wall 10 of cutout 122 has a depending lip 123.

The element 106 of the mechanism 47 is slidably mounted in and depends from the channel 3, and when arranged in the channel 3, the head part 109 and the outset portions 118 of the sides 117 of the yoke coact to retain element 106 in the stock. The head part 109 travels on the tracks 18. The portions 118 are arranged exteriorly of the bottom of the channel. The bridge piece 121 is for the purpose of pushing the cartridges through the channel 3 when element 106 is shifted forwardly. The finger grip 120 is for the purpose of pulling element 106 to the rear end of channel 3 and on such action the members 102, 103 revolve the pick-up mechanism 25 in a clockwise direction thereby winding up the power transmitting spring 80. When element 106 is moved to the position shown in Figure 1b, after the cartridges carried by a clip have been fired, it is latched in such position by a latching means 124 arranged in channel 3 above the tracks 18. The means 124 consists of an upstanding forwardly inclined arm 125 provided at its lower end with a nose 126 for engagement with the forward end edge of the head part 109 of element 106 when the latter is in the position shown in Figure 1b. Integral with the lower end of arm 125, above and in proximity to nose 126 is a rearwardly extending upwardly inclined arm 127 which merges into one end of a split loop 128 mounted on a pin 129 fixed to the lining 16 and disposed transversely of channel 3. The other end of the loop 128 merges into an upstanding forwardly directed arm 130 having its upper portion bearing against a pin 131 anchored to lining 16 and disposed transversely of channel 3. The arms 125, 127, 130 are resilient. The pin 129 suspends the means 124 within channel 3 in a manner tending at all times to position the nose 126 in the path of the forward end of head part 109 50 of element 106. The means 124 is shifted from latching relation from the forward end of head part 109 by the rearmost cartridge carried by a clip when positioning a clip of cartridges into the channel or magazine 3. With reference to 55 Figure 1b the rearmost cartridge of a clip is indicated at 132 and is shown in position to be moved into channel 3. As the rear terminal portion of the clip is moved towards member 2, the said cartridge 132 will contact with arm 125, shifts it upwardly and moves nose 126 from latching engagement with head part 109, as well as shifting the forward portion of the means 124 on pin 129 upwardly from element 106 and rearwardly of the cartridge. The cutout 122 provides a clearance for the rear end of the clip when the latter is inserted in channel 3. The clip when positioned in the channel 3 is arranged over and seats on the base 119 of yoke 116 whereby it 60 is supported at its rear during the removing of the cartridges thereof on the forward movement of the element 106. When the clip has been shifted to dispose the cartridges carried thereby in position to be fed to the pick-up mechanism 70

the forward end of the clip is supported on the upper end of surface 34 (Figure 1^a) which substantially aligns with the upper face of yoke base 119. The portions 118 of the yoke sides 117 provides clearance for the clip when it is supported on the base of the yoke during the forward travel of element 106.

The combined receiver and breech structure generally indicated at 132^a includes a head-piece 133 formed of a central part 134 and a pair of side parts 135, 136 (Figure 11) disposed between the top and horizontal median of part 134. The latter has a pair of vertically aligned spaced openings 137, 138. The opening 137 is of greater diameter than opening 138 and aligns with the said side parts. A pair of oppositely disposed hollow inwardly opening rearwardly extending semi-ovoidal shaped arms 139, 140 are integral with the rear face of parts 135, 136 respectively. The said arms have their inner portions integral with the rear of part 134. The arms 139, 140 provide spaced aligned parallel channels 141, 142 respectively which are closed at their forwards by the side parts 135, 136. The side part 135 is formed with a rectangular passage 143 which opens into the forward end of channel 142. The part 134 below the opening 137 is provided with a transverse opening 144 which intersects the upper portion of opening 138. The part 134 is formed with a forwardly directed annular extension 145 having its inner face providing a continuation of the wall of opening 137. The opening 138 is formed of two different diameters and the portion of greatest diameter which opens at the rear of part 134 is indicated at 146. The junction of the two diameters of the opening 138 provides a shoulder 147. The rear face of part 134 has an annular boss 148 (Figure 22) which has its inner face align with the wall of opening 137. The upper parts of the arms 141, 142 at the rear end terminal portions thereof are connected together by an upstanding bridge piece 149 (Figures 19 and 21) consisting of a pair of oppositely disposed inwardly extending curved lower side portions 150, 151, a pair of vertically disposed upper side portions 152, 153 and a horizontal disposed top portion 154. The portions 150, 151 at the lower ends are integral with the top of the arms 141, 142. The portions 152, 153 are integral with the upper ends of the portions 150, 151, and the portion 154 is integral with the upper ends of the portions 152, 153. The lower face of the portion 154 is dished out at spaced points thereof (Figure 1^a) as at 155, 156 to provide clearances for a purpose to be referred to.

Secured in the opening 137, extension 145 and boss 148 is the rear end terminal portion 157 of the rifle barrel 158. The portion 157 provides a cartridge receiving chamber 159 conforming in contour to the shape of the cartridge. The bore 160 of the barrel leads from the forward end of chamber 159. The barrel 158 includes an annular peripheral shoulder 161 which abuts the forward end of the extension 145. The barrel 158 is arranged within a groove 162 formed in the top of and co-extensive with a hand grip 163. The latter has a lengthwise opening 164 in which is arranged a bearing sleeve 165. The grip 163 is slidably suspended on a bar 166 which extends through the opening 138. The bar 166 is fixed to the part 134 of head 133 by a transversely extending pin 167 mounted in opening 144. The pin 167 also passes through a groove 168 formed in the top of bar 166. The latter projects rear-

wardly from part 134 of head 133. The pin 167 projects laterally in opposite directions from the said part 134 for a purpose to be referred to. The inner or rear end of the grip 163 is normally spaced forwardly from the extension 145 and such end has secured thereto a metallic plate 169. The latter has integral with the upper end of one side thereof a rearwardly extending plunger 170 corresponding in contour to and which passes through passage 143 to engage the breech block 10 to be referred to. An opening 171 is formed in plate 169 for the passage of bar 166.

The element 48 further includes an opening 172 and a tubular extension 173 forming a continuation of the opening 172 and normally spaced rearwardly from the portion 146 of largest diameter of opening 138. When head 133 moves rearwardly on recoil, the said portion 146 of opening 138 provides a clearance or pocket for receiving the extension 173.

The structure 49 includes a casting 174 formed of a rear part 175, an intermediate part 176 and a forward part 177. The part 175 extends above the part 176, and is formed with an upstanding passage 178 having a portion of its lower end 20 registering with a portion of the upper end of opening or passage 15. Secured in the upper portion of part 175 and extending forwardly therefrom into the channels 141, 142 are combined supporting and guide rods 179, 180 respectively having the rear terminal portions of the compression springs 181, 182 mounted thereon. The springs are arranged in said channels between the forward end of the breech block to be referred to and abutment plates 182^a carried by 30 the rods 179, 180. The part 177 is transversely grooved in its upper face as at 183. The groove 183 includes a vertical rear wall 184, a horizontal bottom wall 185 and a front wall 186 of greater cross sectional length than either of the other 40 walls and inclining upwardly from its lower to its upper end. The purpose of groove 183 will be referred to.

The rifle includes a lock element 187 for locking the breech block to be referred to, in position when firing. The element 187 consists of a block 188 having oppositely disposed rearwardly inclined upper and lower bevels 189, 190 respectively, at its front end. The bevel 190 is of greater length than bevel 189 and is for the purpose of 45 riding against the inclined front wall 186 of groove 183. Secured to the sides of block 188 below the top of the latter is a pair of forwardly extending parallel arms 191 arranged at the sides of the part 177 of casting 174 and having their 50 forward ends pivotally mounted on the pin 167 (Figure 11).

The breech block 192 which is reciprocatory consists of a T-casting formed of a head 193 and a stem 194 extending rearwardly from and disposed centrally with respect to the rear face of head 193. The latter is slidably mounted in the channels 141, 142. The head 193 has arranged axially thereof an opening 195 for the pin 196 of a spring controlled firing device 196^a. The head 193 and stem 194 are formed with a chamber 197 for the slidable head of the device 196^a. The head 198 at its forward end is connected to the rear end of the pin 196. Interposed between the forward wall of chamber 197 and the head 198 as well as surrounding pin 196 is a coiled controlling spring 199 for the device 196^a. The stem 194 rearwardly of chamber 197 is provided with a hammer structure chamber 200 which opens at 60 its rear into chamber 201 for a combined abut- 70

ment and keeper member 202. Chamber 201 is formed in the rear end of the stem 194. The chambers 197, 200 communicate. The head 198 normally extends from the chamber 197 into the 5 chamber 200 in the path of the hammer structure. Fixedly mounted in the chamber 201 is the combined abutment and keeper member 202 provided with forwardly extending rod 203 and a beveled lower rear corner 203a. The head 198, in 10 its top is formed with a cutout 204 to provide a pair of spaced abutments 205 for limiting the extent of the forward and rearward movements of the device 196a. There is associated with the shoulders 205 a stop pin 206 arranged within the 15 head 193. The latter pin its top is provided with a groove 207 closed at its rear end, open at its forward end and having its bottom formed with forward and rear cavities 208, 209 respectively. The purpose of groove 207 will be referred to.

20 The top of stem 194 is slotted as at 210.

The hammer structure generally indicated at 211 includes a tubular element 212 positioned in the chamber 200 forwardly of chamber 201. The element 212 is bodily carried with the breech 25 block 192 on both directions of movement of the latter and automatically acts after the breech block has been locked at the extent of its forward movement to impact hammer 198 to provide for the operation of firing device 196a. The element 30 212 is closed at its forward end and open at its rear end. The rear end of element 212 has a vertical lug 213 formed with a rearwardly beveled top edge. The rod 203 extends into element 212, the latter being arranged forwardly of member 35 202. Surrounding rod 203 and interposed between the forward wall 213a on the inner face of element 212 and member 202 is the operating spring 213b for the element 212. The lug 213 on the rearward movement of structure 192 is engaged by the forward wall of slot 210 and carried rearwardly with the breech block on recoil. The rearward or recoil movement of the breech 40 block is had against the action of the springs 181, 182. When the springs 181, 182 become active 45 the breech block is moved forwardly and during such movement the lug 213 will become into engagement with a trigger releasable sear 214 whereby the structure 211 will be held in the position shown in Figure 1a on the seating of the 50 breech block against boss 143. When the means 214 is released the element 212 will become active, that is to say, impact head 198 and provide for the operation of firing device 196a.

The sear means 214 includes a latching member or lever 215 arranged within the bridge piece 149 and formed at its forward end with a depending nose 216 for engagement with lug 213. The lower end of nose 216 is beveled upwardly from rear to front. The member 215 centrally of its 55 top is formed with an upstanding apertured ear 217 which extends in the cutout 155. The ear 217 pivots on a pin 218 carried by bridge piece 149. The sear 214 includes a releasing lever 219 for member 215. The lever 219 has its forward 60 end terminal portion bearing on the rear end terminal portion of the member 215. The lever 219 intermediate its ends has an upstanding apertured ear 220 which extends into the cutout 156. The ear 220 pivots on a pin 221 carried by 65 the bridge piece 149. The rear end of lever 219 has a depending lug 222. The lever 219 is arranged over and extends rearwardly with respect to opening 178. Extending through the openings 178 and 15 is an operating rod 223 for lever 219.

70 75 The rod 223 at its lower end has a crank arm 224

which is slidably mounted in the slot 39 of trigger 37. One of the arms 26 of structure 21 has an inclined slot, not shown, which registers with the slot 39. The crank arm 224 also passes through the slot in the arm 26. The sear 214 includes a controlling spring 225 for the member 215. The forward end of spring 225 is secured to the lower face of the top of bridge piece 149. The spring 225 has a depending curved part 226 at its rear which bears on the member 215 forwardly of the pivot for the latter and normally tends to maintain the nose 216 in the path of the lug 213. It will be assumed that the sear 214 is in the position shown in Figure 9. Now, if the trigger is moved rearwardly, the rod 223 will be moved upwardly, rocking lever 223 in a direction whereby its forward end will be depressed and which in turn will depress the rear end of member 215 against the action of spring 225 and elevate the forward end of member 215 to move nose 216 clear of lug 213 and release the hammer structure 211. The upper end of rod 223 has a reduced part 227 which bears against the lower face of lever 219 and is disposed forwardly of and in proximity to the lug 222.

20 Arranged in the groove 207 is a shell extractor means 228 consisting of a lever 229 having a depending nose 230 at its forward end and a depending apertured ear 231 intermediate its ends extending into the cavity 208. A pin 232 is arranged in the head part 193 of the breech block and provides a pivot for lever 229. The pin 232 extends through the ear 231. Arranged between the base or bottom of cavity 209 and the rear end of lever 229 is a coiled spring 233 which functions to hold the nose 230 in engaged relation with respect to the flange 234 at the butt end of the cartridge. The rear end of the barrel is countersunk, as at 235 to provide a clearance for the forward end of lever 229 to engage the flange 234. 30 The means 228 is bodily carried with the breech block.

35 Secured in the forward part 177 of the casting 174 forwardly of the groove 183 is a spring controlled deflector 236 which is arranged over the 40 arm 32 and in the path of the cartridge shell when the latter is carried with the breech block as the latter moves rearwardly.

45 Upon the discharge of the rifle the combined receiver and breech, the barrel and the breech 50 block recoils on the element 48 and structure 49 and the locking block 188 slides down in the groove 183 to an extent which will allow the breech block to pass unrestricted over the top of block 188. This movement is had against the 55 action of the springs 181, 182. The springs are of proper tension to allow the breech block to continue its rearward travel until the flange 204 of the empty shell strikes the deflector 236 whereby the shell is then thrown from the rifle.

60 While the breech block is at the rear end of its travel, the resilient upper portion 35 of the arm 32 will lift the cartridge into the loading guide and from there into the path of the breech block. On the rearward movement of the breech 65 block, the forward end of the latter will engage the butt end of the cartridge, force the latter into the barrel and at which time the locking block 188 will be moved to engage the beveled corner 203a of member 202 and lock the breech 70 block in position for the next discharge.

75 By removing the pin 167, the breech block lock and also the breech block may be removed from the rifle.

After a cartridge releases the latching means 75

124 from element 106, the structure 47 will be released and the spring motor can now act to feed the cartridges through the medium of the element 106 pulled by the two steel tapes which are connected to the spring controlled compensating rods 104, 105 suspended in and connected to element 106. The portions of the hub 69 upon which the members 102, 103 wind off and on may be termed drums and are of such diameter as to 10 wind in, on each revolution thereof the equivalent of one cartridge for each pair of aligned lugs 84^a of the pick-up mechanism when the latter is operating.

The purpose of the springs 115 on the rods 104, 15 105 is to compensate for any irregularities between the winding in of the cartridges and picking them up by the pick-up mechanism.

The cartridges slide forward in the clip 20 and with the flange of the foremost cartridge entering the notch 41. When a pair of aligned lugs 20 84^a engage the butt end of the cartridge, the latter will be tilted over against aligned edge portions 88 of the discs such as shown in Figure 1^a. The pick-up mechanism will carry the cartridge to the dotted line position shown in Figure 1^a where it will remain until the rifle takes up a leading cartridge.

When the rifle takes up a leading cartridge, it 30 will allow for the pick-up mechanism to revolve to an extent to place a follower cartridge in the position of a leading cartridge. This movement also presses downward the upper resilient portion 35 of arm 32 to a position for acting in lifting the cartridge to the loading guide as beforementioned. As the element 106 moves forwardly, the empty portion of the clip passes through the yoke 116 in proximity to the bottom thereof.

The plunger is employed for initially setting 40 the rifle for loading and firing. Continuous firing of the rifle is had when one presses his finger continuously on the trigger so as to maintain the latching means 214 in inactive position.

What I claim is:

45 1. In a magazine rifle, a revoluble combined cartridge pick-up and delivery mechanism for successively positioning cartridges to be fired, a traveling cartridge feeding mechanism movable towards the delivery mechanism and capable of being shifted rearwardly to set it in initial feeding position; and for coaction with the said other mechanism for successively shifting cartridges in a direction for loading, a power transmitting spring, a shaft operated counter-clockwise by 50 said spring, a hub fixed to the shaft, secured to said mechanisms and common to the latter for operating them in unison, said feeding mechanism when shifted to set it in initial feeding position winding up said spring, said feeding mechanism including a cartridge pusher element, means engaging with said element for latching said feeding mechanism in its initial feeding position, means extending rearwardly from said delivery mechanism providing a cartridge magazine in which said feeding mechanism travels, said magazine having an open bottom, and a cartridge carrying clip for insertion into said bottom for slidably supporting and for positioning cartridges forwardly of said element, said 55 clip when inserted in said bottom providing for one of the cartridges supported thereby shifting said latching means clear of said element to release said feeding mechanism.

2. In a magazine rifle, a pair of axially apertured parallel spaced revoluble discs, each hav-

ing spaced cartridge pick-up lugs extended from its outer edge, the lugs on one disc aligning with the lugs on the other, a cartridge pusher element, a pair of spaced windable tapes for pulling said element in a direction for successively positioning cartridges to be picked up by the pairs of aligned lugs, a hub provided centrally thereof with a flange positioned between and fixed to said discs and a pair of end flanges, each spaced from a side of the central flange, each of said tapes being secured at one end to said hub for winding on and off of the latter between an end flange and the central flange, and a motor operated shaft fixed to said hub.

3. In a magazine rifle, a pair of axially apertured parallel spaced revoluble discs, each having spaced cartridge pick-up lugs extended from its outer edge, the lugs on one disc aligning with the lugs on the other, a cartridge pusher element, a pair of spaced windable tapes for pulling said element in a direction for successively positioning cartridges to be picked up by the pairs of aligned lugs, a hub provided centrally thereof with a flange positioned between and fixed to said discs and a pair of end flanges, each spaced from a side of the central flange, each of said tapes being secured at one end to said hub for winding on and off of the latter between an end flange and the central flange, a pair of spring controlled compensating bars slidably mounted 30 in said element and secured to the other ends of said tapes, and a motor operated shaft secured to said hub for revolving said discs simultaneously with the winding of the tapes on the hub.

4. In a magazine rifle, a pair of axially apertured parallel spaced revoluble discs, each having spaced cartridge pick-up lugs extended from its outer edge, the lugs on one disc aligning with the lugs on the other, a cartridge pusher element, a pair of spaced windable tapes for pulling said element in a direction for successively positioning cartridges to be picked up by the pairs of aligned lugs, a hub provided centrally thereof with a flange positioned between and fixed to said discs and a pair of end flanges, each spaced from a side of the central flange, each of said tapes being secured at one end to said hub for winding on and off of the latter between an end flange and the central flange, a motor operated shaft fixed to said hub, and an upstanding combined cartridge abutment and guide element having a part thereof arranged between and extended from said discs.

5. In a magazine rifle, a pair of axially apertured parallel spaced revoluble discs, each having spaced cartridge pick-up lugs extended from its outer edge, the lugs on one disc aligning with the lugs on the other, a cartridge pusher element, a pair of spaced windable tapes for pulling said element in a direction for successively positioning cartridges to be picked up by the pairs of aligned lugs, a hub provided centrally thereof with a flange positioned between and fixed to said discs and a pair of end flanges, each spaced from a side of the central flange, each of said tapes being secured at one end to said hub for winding on and off of the latter between an end flange and the central flange, a pair of spring controlled compensating bars slidably mounted 70 in said element and secured to the other ends of said tapes, a motor operated shaft secured to said hub for revolving said discs simultaneously with the winding of the tapes on the hub, and an upstanding combined cartridge abutment 75

and guide element having a part thereof arranged between and extended from said discs.

6. In a magazine rifle, a revoluble cartridge pick-up and delivery mechanism for successively positioning cartridges to be fired, a combined trigger, handle and cartridge guiding structure including a stationary combined cartridge supporting, abutting and guiding part extended through said mechanism from the rear of the latter to feeding position and for holding cartridges in the path of said mechanism to be picked up by said mechanism, a stock extended rearwardly from said structure and being formed with a cartridge magazine leading to said cartridge supporting, abutting and guiding part, a traveling cartridge feeding mechanism operating in the magazine for successively positioning cartridges on said cartridge supporting, abutting and guiding part in the path of and to be picked up by said delivery mechanism, and an operating means common to the said delivery and feeding mechanisms.

7. In a magazine rifle, a revoluble cartridge pick-up and delivery mechanism for successively positioning cartridges to be fired, a combined trigger, handle and cartridge guiding structure including a combined cartridge supporting, abutting and guiding part passing through said mechanism from the rear of the latter to feeding position and for holding cartridges in the path of said mechanism to be picked up by the said mechanism, a stock extended rearwardly from said structure and being formed with a cartridge magazine leading to said cartridge supporting, abutting and guiding part, a traveling cartridge feeding mechanism operating in the magazine for successively positioning cartridges on said cartridge supporting, abutting and guiding part in the path of and to be picked up by said delivery mechanism, an operating means common to the said delivery and feeding mechanisms, said feeding mechanism including a cartridge pusher element, said magazine having an open bottom, a clip detachably mounted in the open bottom of the magazine for slidably supporting cartridges forwardly of said pusher element, and said clip being supported by said cartridge supporting, abutting and guiding part and the said pusher element.

50 8. In a magazine rifle, a revoluble combined cartridge pick-up and delivery mechanism for successively positioning cartridges to be fired, a

traveling cartridge feeding mechanism movable towards the delivery mechanism and capable of being shifted rearwardly to set it in initial feeding position and for coaction with the said delivery mechanism for successively shifting cartridges to a position in the path of, to be picked up by and delivered by the delivery mechanism, a power transmitting spring, a shaft operated counter-clockwise by said spring, a hub fixed to said shaft, secured to said delivery and feeding mechanisms and common to the latter for operating them in unison, said feeding mechanism when shifted to set it in initial feeding position winding up said spring, and releasable means for holding the feeding mechanism in its initial feeding position.

9. In a magazine rifle, a revoluble combined cartridge pick-up and delivery mechanism for successively positioning cartridges to be fired, a traveling cartridge feeding mechanism movable towards the delivery mechanism and capable of being shifted rearwardly to set it in initial feeding position and for coaction with the said delivery mechanism for successively shifting cartridges to a position in the path of, to be picked up by and delivered by the delivery mechanism, a power transmitting spring, a shaft operated counter-clockwise by said spring, a hub fixed to said shaft, secured to said delivery and feeding mechanisms and common to the said delivery and feeding mechanisms for operating them in unison, said feeding mechanism when shifted to set it in initial feeding position winding up said spring, releasable means for holding the feeding mechanism in its initial feeding position, said feeding mechanism including a cartridge pusher element, a stock extending rearwardly from said delivery mechanism and provided with an open bottom cartridge magazine, and a clip for slidably supporting cartridges within said magazine forwardly of said pusher element, said clip being removably mounted in said open bottom and supported by said pusher element on the operation of said delivery and feeding mechanisms.

10. The structure as set forth in claim 8 having said feeding mechanism including a cartridge pusher element, a pair of spring controlled compensating bars slidably mounted in said pusher element, and a pair of tapes connected at one end to said hub, winding on and off of said hub and each connected at its other end to a compensating bar.

LOUIS NOLAN NOMAR.
